J. E. Roberts
Atty.

UNITED STATES PATENT OFFICE.

WILLIAM G. HOUSKEEPER, OF NEW YORK, N. Y., ASSIGNOR TO WESTERN ELECTRIC COMPANY, INCORPORATED, OF NEW YORK, N. Y., A CORPORATION OF NEW YORK.

CONTROL APPARATUS FOR EVACUATED VESSELS.

Application filed November 6, 1920. Serial No. 422,200.

To all whom it may concern:

Be it known that I, WILLIAM G. Houskeeper, a citizen of the United States, residing at New York, in the county of New York and State of New York, have invented certain new and useful Improvements in Control Apparatus for Evacuated Vessels, of which the following is a full, clear, concise, and exact description.

10 This invention relates to control apparatus for evacuated vessels. More particularly, it relates to means and methods for controlling the intensity of ionization within an evacuated vessel.

15 It is well known that vacuum tubes of the electron discharge type are provided with a heated cathode which serves as the source of electrons. As described in the United States patent to Buckley, No. 1,372,798, patented

20 March 29, 1921, such a tube may be used as a vacuum gauge, the ionization of the gas being a measure of the gas pressure. It has been discovered that fluctuations in the gas pressure within the vacuum tube give

25 corresponding fluctuations in the intensity of the electron discharge from heated filament. For some gases as oxygen for example the thermionic activity of the filament varies inversely with changes in the pressure;

30 for other gases, such as hydrogen, the thermionic activity varies directly with the pressure. These fluctuations in the intensity of electron discharge from the heated filament are objectionable, and in the case

35 of the vacuum gauge lead to inaccurate results in measuring the gas pressure.

An object of the present invention is to prevent the variations in pressure from producing fluctuations in the intensity of the 40 electron discharge from the heated cathode and to insure that the intensity of the anode-cathode current shall be constant over a wide range of gas pressures. This is preferably accomplished by having the electron or space

45 current in the vessel operate a translating device, which, in turn, controls, in a suitable manner, the amount of current supplied to the filament or cathode. For example, the translating device may comprise a relay

50 responsive to changes in the space current of the tube for short circuiting the filament at such a rate that the average current supplied to the filament for heating the same is of such value as to produce the constant

55 space current desired.

This invention will be better understood by reference to the following detailed description taken in connection with the accompanying drawing, which shows, in connection with a vessel to be evacuated, an ionization manometer, the action of which is regulated in accordance with this invention.

Referring to the drawing, 4 and 5 represent vessels, gas pressure in which is to be measured. A connecting tube 6 extends from these vessels to a vessel 7 in which there are enclosed a source of electrons 8 and an electrode 9 serving as an anode. Connected between electrodes 8 and 9 is a resistance element 10 supplied with current from a battery 11 in such a manner that the RI drop in resistance 10, produces the desired potential difference between the electrodes 8 and 9. Battery 11 also serves to supply heating current to cathode 8 since one terminal of the cathode is connected to the positive pole of battery through resistance 10 and its other terminal is connected to the negative pole of battery through a resistance element 12. With these connections, electron current will flow from cathode 8 to anode 9. The third electrode 13, of the tube is maintained at a negative potential with respect to cathode 8 by an amount equal to the RI drop in resistance 12.

If the space within the vessel 7 is a perfect vacuum, the space current between the members 8 and 9 will be a pure electron current, the only source of carriers being the cathode 8. Inasmuch as the negatively charged electrons from the element 8 can pass only to an electrode which is at a higher potential, it will be apparent that no current can flow to it from the third electrode 13. If, however, there is present a small amount of gas and the RI drop across resistance 10 is sufficiently high, the electrons will acquire sufficient velocity to ionize some of the gas molecules and there will be present both negative and positive ions. The positive ions will travel to negatively charged electrodes and chiefly to that one which is at the lowest potential, that is, to the electrode 13. The collection of positive charges on this electrode will give rise externally to a current from this electrode to the cathode, and the presence of this current may be detected by the insertion of any suitable current measuring instrument, such

as a galvanometer 15. Since, for a given setting of the system, the amount of this current will be proportional to the pressure, the deflection of the instrument 15 will be 5 an indication of the degree of evacuation present in the vessel.

In the calibration of such a device it has been found convenient to calibrate for constant space current in the manometer. It is 10 therefore, desirable when measuring pressure by means of this gauge, that the space current should be maintained at this value, which as has been pointed out, would require frequent adjustment with changes in 15 pressure. In accordance with this invention, automatic means is provided for maintaining the space current at a desired value. The preferred way of accomplishing this, as shown in the accompanying drawing, consists 20 in having the anode-cathode current pass through a relay 19 which controls the short circuit between the terminals 20, 21 of filament 8. The armature 22 of relay 19 is normally out of contact with point 24 so that 25 heating current is supplied to the filament. When the current flowing through the relay 19 is sufficient to cause its armature to be attracted, a short circuit around the terminals of cathode 8 is made, so that practically 30 no heating current is supplied to cathode 8 while armature 22 is in contact with point 24. This short-circuiting of the cathode, of course, permits the cathode to cool thereby decreasing the anode-cathode current, until 35 the anode-cathode current has been decreased to such a value as to permit armature 22 to move back to its position. In the operation of the device, relay 19 is so adjusted that the cathode 8 is short circuited at such a rate 40 that the average temperature of the cathode is sufficient to maintain the desired constant value of the anode-cathode current. The connections from battery 11 to cathode 8 should also be so adjusted that when cathode 45 8 is not short circuited the heating current will be so large as to furnish at least the desired anode current whatever the pressure of the gas in the vessel.

If desired, a suitable current measuring 50 instrument, such as a milliammeter 27 may be inserted in the circuit between the anode 9 and the cathode 8 in order that the anode-cathode current may be observed. The absolute value of this current may be determined initially, by suitable adjustments of 55 relay 19. The tension of the spring (not shown) for the movable contact may be varied for example in order to make the usual preliminary adjustment.

If the current supplied to cathode 8, when 60 it is not short circuited, is sufficient to give the desired space current even when the tube is evacuated to the greatest possible extent, the device 15 has been found, in one 65 particular case, to furnish qualitative indi-

cation of the pressure from a pressure of about .25 mm. of HG down to about .035 mm. of HG, while it furnishes a strictly accurate indication of the pressure from .035 mm. down to the lowest pressure obtainable. For any pressure up to .035 mm. the temperature required by the cathode will be intermediate its temperature when short circuited and its temperature with maximum heating current. The regulating means of this invention furthermore allows the manometer to be put in operation when the tube is at atmospheric pressure and maintained in condition for operation without any manual adjustments during the process 75 of evacuating the tube to the lowest pressure obtainable.

It is obvious that various modifications may be made in the structure of the system above described, without departing, in any 80 wise, from the spirit of the invention as set forth in the appended claims.

What is claimed is:

1. The combination of a vacuum tube subject to different degrees of vacuum, a cathode in said tube, means for producing an electron stream from said cathode, and means comprising a short circuit for said cathode and responsive to a change in the degree of the vacuum of said tube for regulating the intensity of said stream while permitting the degree of vacuum of said tube to remain substantially constant during the regulation of said stream.

2. The combination of a vessel containing 100 a plurality of electrodes, means for causing one of said electrodes to emit electrons, and means responsive to changes in the pressure of said vessel for intermittently short-circuiting said cathode whereby the emission 105 from said cathode is regulated by the pressure in said vessel while still permitting the degree of vacuum of said vessel to remain substantially constant during the regulation of said emission.

3. A vessel containing a plurality of electrodes, one of which is a cathode, another of which is an anode, means for establishing a space current between said anode and cathode, means for supplying heating current to said cathode, and means connected in circuit between said anode and cathode and responsive to current changes produced by variations in the pressure within said vessel for intermittently reducing the heating current through said cathode substantially to zero.

4. A vessel containing a plurality of electrodes, means for causing one of said electrodes to emit electrons, means for controlling the rate of emission of electrons from said source in accordance with the pressure within said vessel, said second means comprising a translating device whose operation is dependent upon the rate of electron 125 130

emission, and a short circuit for said cathode and controlled by said translating device for regulating said first mentioned means.

5. A vessel containing a plurality of electrodes, one of which is a cathode and another an anode, means for supplying space current between said anode and said cathode, means for supplying heating current to said cathode, and means for causing the intensity of said space current to be practically independent of changes in the pressure of said vessel over a wide range, said means comprising means connected between said anode and cathode and responsive to 15 changes in the space current produced by pressure variations for intermittently reducing substantially to zero the heating current supplied to said cathode.

6. A vessel containing a plurality of electrodes, a source of current for heating one of said electrodes, whereby said electrode is made a source of electrons, connections for shunting said cathode by a path of lower resistance than said cathode, and means for 25 intermittently varying said connections whereby the electron emission from said electrode is made practically independent of changes in the pressure in said vessel.

7. The combination of a vessel subject to 30 different degrees of vacuum, means for supplying said vessel with an electron stream, and a relay responsive to the degree of vacuum in said vessel for intermittently tending to reduce said electron stream to zero in response to changes in the degree of 35 vacuum of said vessel.

8. The combination of a vessel subject to 40 different degrees of vacuum, an electron discharge tube associated therewith, connections for removing gas from said vessel, said tube having a cathode and an anode, and means for intermittently short-circuiting said cathode in response to the degree of 45 vacuum of said vessel.

45. 9. A tube containing an anode and a

cathode, means for establishing space current between said anode and cathode, a vessel adapted to be evacuated and associated with said tube, a relay whose operation is controlled by said space current, and connections controlled by said relay for intermittently short-circuiting said cathode whereby the space current in said tube is made practically independent of the pressure in said vessel. 50 55

10. A vessel subjected to different degrees of vacuum and comprising an anode and a cathode, and means for short-circuiting said cathode in response to variations in said pressure. 60

11. In combination, a vessel subject to different degrees of pressure, and comprising an anode and a cathode, and means responsive to the pressure of said vessel for short-circuiting said cathode when said pressure exceeds a predetermined value. 65

12. In combination, a vessel to be evacuated, a vacuum tube subject to the same pressure variations as said vessel, and comprising an anode and a cathode, means for measuring the relative amount of positive ionization in said tube whereby the pressure in said vessel may be determined, means for supplying space current between anode and cathode, and means responsive to pressure changes in said tube for intermittently short-circuiting said cathode whereby said space current may be made substantially independent of said pressure variations. 70 75

13. An electric discharge device subject to 80 variations in an operating characteristic thereof and comprising an anode and a cathode, and means for short-circuiting said cathode in response to variations in an operating characteristic of said device. 85

In witness whereof, I hereunto subscribe my name this 1st day of November, A. D. 1920.

WILLIAM G. HOUSKEEPER.
